CLAIM

I claim the ornamental design for a table planter, as shown and described.

DESCRIPTION

FIG. 1 is a top perspective view of a first embodiment of a table planter of the present application;

FIG. 2 is a bottom perspective view of a first embodiment of a table planter of the present application;

FIGS. 3-8 are, respectively, front, right side, top, rear, left side and bottom orthogonal views of the first embodiment of a table planter;

FIG. 9 is a top perspective view of a second embodiment of a table planter of the present application;

FIG. 10 is a bottom perspective view of a second embodiment of a table planter of the present application;

FIGS. 11-16 are, respectively, front, right side, top, rear, left side and bottom 20 orthogonal views of the second embodiment of a table planter;

FIG. 17 is a top perspective view of a third embodiment of a table planter of the present application;

FIG. 18 is a bottom perspective view of a third embodiment of a table planter of the present application; and,

FIGS. 19-24 are, respectively, front, right side, top, rear, left side and bottom orthogonal views of the third embodiment of a table planter.
